US0D1090045S

(12) **United States Design Patent** (10) **Patent No.:** **US D1,090,045 S**
(45) **Date of Patent:** **** Aug. 26, 2025**

(54) **TOOL BOX**

(71) Applicant: **MING SHIN TOOLS CO., LTD.**,
Taichung (TW)

(72) Inventor: **Yung-Shun Chen**, Taichung (TW)

(73) Assignee: **MING SHIN TOOLS CO., LTD.**,
Taichung (TW)

(**) Term: **15 Years**

(21) Appl. No.: **29/919,095**

(22) Filed: **Dec. 1, 2023**

(51) LOC (15) Cl. **03-01**

(52) U.S. Cl.

USPC **D3/276**; D3/905; D3/282

(58) **Field of Classification Search**

USPC D3/905, 276

CPC B25H 3/02; B25H 3/00

See application file for complete search history.

(57) **CLAIM**

The ornamental design for a tool box as shown and described.

DESCRIPTION

FIG. 1 is a top, front, and right perspective view of a tool box showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, rear, and left perspective view thereof.

The broken lines in the drawings illustrate portions of the tool box which form no part of the claimed design.

1 Claim, 6 Drawing Sheets
